CLAIM

The ornamental design for an electronic device mount, as shown and described.

DESCRIPTION

FIG. 1 is a front perspective view of an electronic device mount according to the present invention;

FIG. 2 is a rear perspective view of the electronic device mount;

FIG. 3 is a front view of the electronic device mount;

FIG. 4 is a rear view of the electronic device mount;

FIG. 5 is a left side view of the electronic device mount;

FIG. 6 is a right side view of the electronic device mount;

FIG. 7 is a top view of the electronic device mount; and,

FIG. 8 is a bottom view of the electronic device mount.

The broken lines shown in the drawings represent portions of the electronic device mount that form no part of the claimed design.

1 Claim, 4 Drawing Sheets
